UNITED STATES PATENT OFFICE.

JOHN N. CHILDS, OF HAZLETON, PENNSYLVANIA, ASSIGNOR TO INTERNATIONAL STEAM PUMP COMPANY, A CORPORATION OF NEW JERSEY.

PUMP.

1,164,168.

Specification of Letters Patent. Patented Dec. 14, 1915.

Application filed June 14, 1913. Serial No. 773,682.

To all whom it may concern:

Be it known that I, JOHN N. CHILDS, a citizen of the United States, residing at Hazleton, county of Luzerne, and State of Pennsylvania, have invented certain new and useful Improvements in Pumps, fully described and represented in the following specification and the accompanying drawings, forming a part of the same.

10 This invention relates to an improved pump construction, and especially to an improved arrangement of cylinder lining or piston sleeve and means for holding it in place, by which the size of the pump is reduced and a cheaper and better construction secured.

The usual practice in pumps employing piston sleeves separate from the other parts of the pump has been to hold these in place by an end flange bolted to the barrel casing. This flange extending outside the cylinder bore necessarily increases the size of the end plunger chamber and, in that class of pumps employing suction and discharge 20 valves on opposite sides of the chamber, requires that the suction valves be lowered and discharge valves raised beyond what otherwise would be necessary. The opening at the end of the plunger chamber, also, must be large enough to remove the flange, thus increasing the size of this opening and its cover beyond what would be necessary for a plain sleeve, which correspondingly raises the discharge valves and lowers the suction 30 valves. This use of the end flange, therefore, increases largely the height and weight of the barrel. I avoid the above objections to the flanged sleeve, and greatly reduce the weight of this type of pump and its 35 cost by the present construction, in which the piston sleeve has no end flange, but is held in place by a clamping ring set into a groove in the outside of the piston sleeve and secured in place, preferably by bolting 40 the clamping ring between flanges on the front and rear barrels, in that type of pumps in which such separate end barrels are used. The clamping ring is preferably split so 45 that it may be tightened on the sleeve and may be put in place and removed without removing the end barrel.

In the accompanying drawings forming a part of this specification, the invention is illustrated as applied in its preferred form

to a pump of common type and this construction will now be described in detail and the features forming the invention then specifically pointed out in claims.

In the drawing, Figure 1 is a vertical, central longitudinal section of the pump. Fig. 2 is the cross section on line 2 of Fig. 1.

Referring to the drawing, in which the pump shown is of the well-known type of small, light pump used especially for pumping oil on shipboard or oil barges, and formed of front and rear barrels, each carrying a single bottom suction valve and a single top discharge valve; A is the front plunger chamber, B the rear plunger chamber, a suction valves, b the discharge valves, C the suction chambers, D the discharge chambers, E the suction main, F the discharge main, G the piston or plunger, and H the plunger rod. The barrels are formed with the usual flanged sleeves 10, by which the plunger cylinder is formed between the barrels, and, in accordance with the present invention, the piston or plunger sleeve c is a plain sleeve, without flange, and secured in place by a split or two-part ring d entering a groove 1 formed in the outside of the sleeve, the two parts of the clamping ring d being shown as secured together by bolts 2, and the barrel flanges being bolted together with ring d between them by bolts 3 passing through the barrel flanges and ring. The suction and discharge valves a, b, are shown as of the common type, with the valves held in place by crabs 4 on valve stems 5 so as to be readily removable, the usual openings and caps 7 at the tops of the barrels being provided for the removal of the discharge valves.

It will be seen that, in the construction shown, the inner diameter of the rear plunger chamber and the rear opening need be no larger than is necessary for the pump cylinder and piston sleeve of the size required, so that the suction valves may be raised and the discharge valves lowered, and brought nearer the pump cylinder, it being unnecessary to provide a chamber and opening of the increased size necessary to accommodate the usual flange extending outside the piston sleeve. This not only reduces greatly the weight of the pump barrel and cost of material, but also it does away with the machining for the sleeve

flange which is a very long and expensive 5 operation of boring, and with drilling, tapping, studding, etc. The raising of the suction valve to approximately the level of the cylinder bore, also, secures increased efficiency and enables the pump to be made somewhat smaller, as the fluid handled is discharged through the suction valve directly into the large chamber space opposite 10 the cylinder, instead of into spaces around the valve below the flange as in the old flanged sleeve construction.

It will be understood that the broader 15 features of the invention are not limited to a pump of the special type shown, but are applicable generally in pump constructions employing piston sleeves. For instance, in 20 some types of pump, it is the custom to insert bronze or other metal sleeves under hydraulic or similar pressure, and renewal of such sleeves requires that they be cut out and thus destroyed, while the present invention provides for the cheap and convenient substitution of a new sleeve when necessary. 25 While the split clamping ring and grooved piston sleeve is the preferred means of holding the piston sleeve in place, especially in pumps of the type shown, it will be understood that the invention, considered broadly, 30 includes other means for removably securing the piston sleeve in place.

What is claimed is:

1. A pump having a cylinder provided 35 with a piston sleeve forming a lining for the cylinder and having an exterior groove, a clamping device entering said groove for holding the sleeve against endwise movement, and means accessible outside the cylinder for securing said clamping device in 40 place on the cylinder and releasing it for withdrawal from the groove transversely to the cylinder without moving the cylinder, whereby the piston sleeve may be inserted

and drawn out without moving the cylinder endwise. 45

2. A pump having its cylinder divided transversely, and having a piston sleeve forming a lining for the cylinder and secured in place by a split clamping ring engaging the exterior of the piston sleeve and detachably held in place between the two parts of the pump cylinder, said ring being free to be removed transversely to the sleeve between the parts of the cylinder by detaching the holding device without moving 50 either part of the pump cylinder. 55

3. A pump having an end chamber provided with a rear opening, suction and discharge valves on opposite sides of said chamber, a pump cylinder extending from the chamber on the side opposite and in line with the rear opening, a removable piston sleeve forming a lining for the cylinder and adapted to be drawn outward through the end chamber and rear opening, and a clamping device engaging the exterior of said sleeve between its ends for holding the sleeve in place, said clamping device being removable transversely to the sleeve to release the sleeve for its withdrawal without moving 65 the pump cylinder. 70

4. A pump having end barrels provided with flanged extensions forming a transversely divided cylinder, suction and force valves on opposite sides of the plunger 75 chambers, piston sleeve *c* having exterior groove 1, and split clamping ring *d* entering said groove and bolted in place between the flanges of the pump barrels.

In testimony whereof, I have hereunto set 80 my hand, in the presence of two subscribing witnesses.

JOHN N. CHILDS.
